ABSTRACT OF THE DISCLOSURE

A pawl and ratchet assembly for an electromechanical timepiece is provided with a variably settable mounting means mounting the ratchet wheel and return pawl for movement together relative to the drive pawl to variably set the phase relationship between the drive and return pawls. The drive pawl is mounted on an electrically maintained mechanical resonator and the ratchet wheel and return pawl are mounted for movement together on a movable plate member.

The present invention relates to a pawl-ratchet wheel assembly for electro-mechanical timepieces whose time base and motor are constituted by a mechanical resonator which is electrically maintained. The pawl and ratchet assembly comprises a driving pawl driving a ratchet wheel in one direction, a return pawl preventing a rotation of the ratchet wheel in the opposite direction and a device for adjusting the relative phase of the driving and return pawls.

Already known in the prior art is a pawl-ratchet wheel assembly for an electro-mechanical watch whose time base comprises a mechanical resonator carrying a driving pawl acting on a ratchet wheel whose rotation in the opposite direction is prevented by a return pawl and comprising a device operative to adjust the pressure of the return pawl and which operates at a relatively low frequency.

It has been found however that in the pawl-ratchet wheel devices used for transforming high frequency mechanical oscillations into rotational movement that the adjustment of the pressure of the return pawl on the ratchet wheel does not constitute a sufficient adjustment and hence, that it would be desirable to provide a device for adjusting the relative phase of the ends of the pawls.

The adjustment of the relative phase of the pawls should preferably take place independently of the adjustment of the pawl pressure. This means that once the relative phase is adjusted, it cannot be modified by a subsequent adjustment of the pawl pressure.

To this effect, there has been proposed a construction in which the device for adjusting the relative phase of the pawls acts on the return pawl by moving this return pawl tangentially to the ratchet wheel. In this assembly, the device for adjusting the pressure of the return pawl is independent of the phase adjustment. While this construction gives satisfactory results, it is however complicated and costly.

The present invention has for its primary objective to provide a pawl-ratchet wheel assembly having means for adjusting the relative phase of the pawls and which is of a simple construction and therefore easier to manufacture on a large scale.

The pawl-ratchet wheel assembly of the present invention is particularly designed for electro-mechanical timepieces whose time base and driving member are constituted by a mechanical resonator which is electrically maintained. The pawl and ratchet wheel comprises a driving

2

pawl driving a ratchet wheel in a given direction, a return pawl preventing rotation of the ratchet wheel in the opposite direction and a device for adjusting the relative phase of the driving and return pawls. The device for adjusting the phase acts on the ratchet wheel in such a way that the ratchet wheel moves with the return pawl relative to the driving pawl.

The accompanying drawing represents by way of example one embodiment of the subject of the invention.

The single figure of the drawing schematically represents, in partial section, an electro-mechanical timepiece movement comprising essentially a mechanical resonator 1 secured by its foot 1a on a plate 2. The resonator comprises two oscillating branches 1b and 1c which are electrically maintained by means of transducers. Branch 1b carries a driving pawl 3 which is not directly embedded in a branch of the resonator, but rather is mounted in a rectangular bar 4 secured on the resonator by means of a pin 5 located at one end of bar 4 in order to be able to rotationally move under the action of a lateral force exerted on the free end of the bar. The driving pawl engages in the teeth of a ratchet wheel 6 whose pinion 7 is constituted by a polarized polar wheel magnetically driving a magnetic wheel 8 whose pinion 9 meshes with a first intermediate wheel 10 which is connected to drive the other gears of the timepiece movement.

Instead of a magnetic driving, it would also be possible to provide a mechanical driving, such as by a toothed wheel.

Wheels 6 and 8 are pivoted in an auxiliary cage constituted by two bridge plate members 11 and 12 secured, respectively, on the upper and lower sides of foot 1a of the resonator.

The lower bridge plate member 12 is of simple form while the upper bridge plate member 11 has a more complicated shape including cut-outs or slots 16 and 18 whose two sides are connected, respectively, by adjusting screws 17 and 19. The purpose of the slots 16 and 18 is to render the plate member 11 flexible, as described in more detail below. The return pawl 14 is embedded at an end portion 20 of the plate 11 which can be bent or flexed by screw 19 to adjust the pressure of the return pawl. Screw 17 serves to adjust the relative phase of the end of the pawl as will be described later.

The upper bridge plate member 11 is divided by the slot 16 into two zones, a foot portion 11a secured to the foot of the resonator by a screw and two positioning pins 13 and 15 and a free zone portion 11b connected to foot 11a by an elastically deformable portion 11c. The end portion 20 is integral with the free zone 11b and moves therewith when adjusting screw 17 is acted upon.

In operation, the screw 17 is either tightened or loosened to effect pivotal movement of the free zone portion 11b of the plate member 11 either towards or away from the stationary foot portion 11a. The movement of the free zone portion 11b carries with it both the ratchet wheel 6 and the return pawl 14 and hence, by merely adjusting the screw 17, the phase relationship between the drive pawl 3 and the return pawl 14 is selectively adjusted. When the free zone portion 11b is moved, the axis of the ratchet wheel is then no longer exactly perpendicular to the trajectory of the driving pawl. It has been proven however that this condition is not absolutely necessary for a proper functioning of the assembly. However during oblique movement of the axis of the ratchet wheel, the ratchet wheel must be moved relative to the driving pawl in such a way that the relative movement of the ratchet wheel and of the driving pawl at their contact point be a tangential movement. It is for this reason that in the particular case where the ratchet wheel and its pinion are pivoted between the two bridge plate members that the device for adjusting the phase has been provided

on the bridge which is nearest to the ratchet wheel, in this instance, the upper bridge plate member.

The pivoting point of the movable, free zone portion 11b of bridge plate member 11 located in part 11c is at least approximately on a line connecting the contact point of the driving pawl on the ratchet wheel and the axis of this ratchet wheel. The axis of gear 8 driven by the pinion of the ratchet wheel is preferably located near the pivoting point of the free zone portion 11b, and the position of this gear will be practically unchanged during movement of the ratchet wheel.

The bridge plate member 11 carrying all the means for adjusting the assembly can thus be easily manufactured, as for example, by stamping.

What is claimed is:

1. A pawl and ratchet assembly for an electromechanical timepiece comprising: a rotatably mounted toothed ratchet wheel; a drive pawl; an electrically maintained mechanical resonator; means mounting said drive pawl on said resonator to effect intermittent rotation of said ratchet wheel in a given direction in response to vibrational movement of said resonator; a return pawl operative to prevent rotation of said ratchet wheel in a direction opposite to said given direction; and variably settable mounting means mounting said ratchet wheel and return pawl for movement together relative to said drive pawl to variably set the phase relationship between said drive and return pawls.

2. An assembly according to claim 1; wherein said variably settable mounting means comprises a plate member, means mounting said ratchet wheel for rotational movement on one portion of said plate member, means mounting said return pawl on said one portion of said plate member in releasable engagement with said ratchet wheel, means for rendering said one portion of said plate member movable with respect to the remaining portion of said plate member, and means for selec-

tively varying the movement of said one portion with respect to said remaining portion to effect movement of both said ratchet wheel and return pawl relative to said drive pawl.

5 3. An assembly according to claim 2; wherein said means for rendering said one portion of said plate member movable with respect to the remaining portion of said plate member comprises means defining a slot in said plate member dividing same into said one portion and remaining portion and effective to render said plate member flexible, and wherein said means for selectively varying the movement of said one portion with respect to said remaining portion comprises means for selectively varying the dimension of said slot to effect movement of said one portion towards and away from said remaining portion.

10 4. An assembly according to claim 3; wherein said slot extends inwardly towards the center of said plate member, and wherein said means for selectively varying the dimension of said slot comprises screw means operative to effect pivotal movement of said one portion about a point located in said remaining portion in the vicinity of the innermost extension of said slot.

15 5. An assembly according to claim 3; further including means on said plate member for adjusting the contact pressure between said return pawl and ratchet wheel.
